RICI LAUNDRY MACHINERY COMPANY, OF BOSTON, MASSACHUSETTS, A CORPO-
RATION OF MASSACHUSETTS

CLAPPER VALVE

Application filed May 1, 1929. Serial No. 359,643.

This invention relates to clapper or exhaust valves for the quick discharge of the contents of washing and other machines where a large quantity of liquid is desired.

In the drawings of one embodiment of my invention selected for illustration and description,

Fig. 1 is a lower face view of a casing or container with my novel valve thereon;

Fig. 2, a vertical cross-section on an enlarged scale, on the line 2—2, Fig. 1;

Fig. 3, a similar view showing the gate open;

Fig. 4, a rear edge view on a reduced scale of the gate closed, the locking detent being removed.

Fig. 5, a vertical longitudinal section on the line 5—5, Fig. 1, reversed showing the means for locking the clapper carrying posts; 20 and

Fig. 6, a plan of the post locking yoke.

Referring first to Figs. 1, 2, my novel valve is shown as comprising a head or clapper 1, of suitable size and configuration provided 25 with a gasket 2.

The head, as shown, is rectangular in outline and is carried yieldingly by springs 3 on posts 4, which extend down through and are movable in spaced arms 5 connected by a 20 bridge member 6 carrying at its rear side a toe 7, all forming what may be called a clapper locking member or support 8. The front end of this member is bent upwardly and carries a pin 9 which rests in an open slot 10 35 in ears 11 on the body 12.

This body is a rectangular one and is bolted to angle plates or brackets 13, which, in turn, are conveniently secured to the casing 14 about the discharge opening 15 therein. The 40 springs 3 seat at one end against the clapper 1, and at their opposite ends against the upper face of the bridge member 6.

The upper face of the clapper 1, Figs. 5, 6, is partly countersunk and receives therein a 45 yoke 16, the forked ends 17 of which receive respectively the reduced upper ends 18 of the posts 4 and thus keep them from dropping from the clapper.

For retaining the locking member 8 in 50 locked position, I provide, Figs. 2, 3, a curved

detent 19, pivoted at 20 to the ear 21 on the body. On this detent is adjustably secured a block 22 provided with a lip 23 to receive the toe 7 of the member 8, the block, by its weight being sufficient to cause the lip normally to 55 be positioned as in Fig. 2 to receive the member 8.

For controlling the position of this lip member, when locking or unlocking the member 8, there is provided a trip or treadle member 24 pivoted at 25 to the member 8 and having at its rear end a beveled nose 26 and at its forward end a foot rest on pedal 27 for operating it. This trip member is relatively narrow, Fig. 1, and extends rearwardly through 60 a slot 28 in the bridge 6 and, Figs. 2, 3, overlies the lip 23.

In operation, if the valve is locked as in Figs. 1, 2, to unlock it and exhaust the contents of the casing or container, the operator lifts the forward end of the trip member 24 with his foot, thus throwing the beveled rear end downwardly against the lip 23 and causing it to swing rearwardly on the pin 20 and freeing the toe 7 of the member 8, permitting the valve to drop as in Fig. 3. To prevent the member 24 from dropping too far, I provide it with a neck 28 in which is a pin 29 which engages the member 8 and thus acts as a stop for the member 24. 75

Or if preferred, to unlock the valve, the operator may give the pedal 27 a quick downward thrust throwing the opposite end of the member 24 upwardly against the curved portion of the detent 19 and the nose 7 of the locking member slightly outward against the beveled forward wall of the detent 22 which will be sufficient to cause it to swing outwardly on the pin 20 and release the bar 24 or give the elbow of the member 8 a kick 85 causing the nose 7 to spring upwardly against the yielding spring 3, and throwing the detent 22 outwardly to free it from the nose 7.

To close and lock the valve, the operator presses downwardly with his foot upon the rest 27 and thus throws the opposite or rear end of the member 24 upwardly against the under side of the lip 23 causing it and the detent 19 to swing outwardly and permit the toe 7 of the member 8 to pass upward past 90

the detent and become locked thereby as it swings back into position, Fig. 2.

It will be appreciated of course that the gasket 2 must be frequently renewed as it gets very hard usage. It will also be obvious that where the valve is being repeatedly opened and the contents of the container dumped, the conditions beneath the container or casing must be very wet and untidy and that beneath the casing is a very difficult place in which to do work such as changing gaskets.

By my novel construction the whole valve construction can be removed bodily, by lifting it, when unlocked, upwardly and forwardly to free the pin 9 from the slot 10 and the unit carried to a convenient and dry place in which to work.

This will also shorten very much the time for doing the work. It will be observed that there are no auxiliary valve parts attached to the casing for operating the valve but parts are all carried by the valve structure as a unit.

The foregoing construction is very simple and effective and much easier to install, remove and repair than any other construction that I know of.

My invention is not restricted to the particular embodiment thereof described and illustrated herein.

30 Claims:

1. A clapper valve comprising a body, a locking member pivoted thereon, a detent pivoted above but effective below and for the member, a clapper carrying bridge on the locking member, a relatively adjustable clapper thereon, and means on one end of the locking member for swinging it and to raise the opposite end and swing the detent outwardly to free it from the locking member.

40 2. A clapper valve comprising a body, a bridge supporting locking member movable thereon, a clapper yieldingly mounted upon the locking member, and a detent member for the latter with a lip thereon and a wall extended upwardly therefrom so that upward movement of the nose of the locking member will strike said wall, and swing the detent away from the locking member.

3. A clapper valve comprising a body, a locking member pivoted thereon, a clapper supporting bridge member on the locking member, a clapper thereon, a detent for the locking member, and a trip member constructed and arranged to engage the detent to cause it to hold and to release the locking member.

4. A clapper valve comprising a body, a clapper carrying locking member thereon, a pivoted detent therefor, a bridge member on the locking member, a clapper thereon, and a trip member extended through the bridge, and engaging the detent.

5. A clapper valve comprising a body, a clapper carrying locking member thereon, a detent pivoted on the body, a bridge on the

locking member, a clapper yieldingly mounted on the bridge, and a trip member having a sliding engagement with the detent to cause it to release the locking member.

6. A clapper valve comprising a body, a locking member movable thereon, a detent for the locking member, a spring supported clapper on the locking member, and a pivoted trip member to free the locking member from the detent by downward movement ahead of the locking member.

7. A clapper valve comprising a body, a locking member thereon, a detent for and normally positioned beneath the locking member and a trip member movable separate from the locking member to swing the detent out of the path of the latter preparatory to locking and unlocking the latter.

8. A clapper valve comprising a body, a clapper, a clapper locking member on the body, a detent for the locking member and a trip member for the detent, the detent fashioned and mounted to be responsive to a quick downward movement of the trip member to unlock the locking member and responsive to a slow upward movement of the locking member to lock the locking member.

9. A clapper valve comprising a body having a curved flange on one side thereof, a locking member pivotally supported on said flange, a detent for the member, a clapper carrying bridge on the locking member, a clapper thereon, and a trip member movably mounted on the locking member.

In testimony whereof, I have signed my name to this specification.

RALPH S. CLARKE.
